United States Patent Office

Des. 214,101
Patented May 6, 1969

214,101

BOAT

Terry J. Simpkins, Dublin, Ohio, assignor to Slickcraft
Boat Company, Holland, Mich., a corporation of
Michigan

Filed Oct. 7, 1968, Ser. No. 13,863

Term of patent 14 years

Int. Cl. D12—06

U.S. Cl. D71—1

FIG. 4.

FIG. 5.

FIG. 1 is a side elevational view which represents the design of my invention;

FIG. 2 is a rear elevational view of the boat shown in FIG. 1;

FIG. 3 is a front elevational view of the boat shown in FIG. 1;

FIG. 4 is a top, perspective view of the boat looking at it from the front; and

FIG. 5 is a top, perspective view looking at the boat from the rear.

The dominant features of my design reside in the portions shown in full lines.

I claim:

The ornamental design for a boat, substantially as shown and described.
